(57) **CLAIM**

The ornamental design for a protective strip with magnet for car doors, as shown and described.

DESCRIPTION

FIG. 1 is a top, front, and side perspective view of a protective strip with magnet for car doors;

FIG. 2 is a front elevation view thereof; wherein the rear elevation view is a mirror image thereof;

FIG. 3 is a left side elevation view thereof; wherein the right side elevation view is a mirror image thereof;

FIG. 4 is a top plan view thereof;

FIG. 5 is a bottom plan view thereof;

FIG. 6 is a cross-sectional view taken at line 6-6 shown in FIG. 1; and,

FIG. 7 is a bottom plan view thereof, wherein the protective strip with magnet for car doors is shown paired with a second strip directly above and affixed to an environmental subject of an automobile.

The broken lines shown in the drawings that illustrate an environmental automobile and cutaway symbols form no part of claimed design. The cutaway symbols illustrated in broken lines in the drawings indicate a symbolic break in the length of the design for a protective strip with magnet for car doors indicating an indeterminate length. The appearance of any portion of the article between the break lines forms no part of the claimed design.
